COMBINATION COIN AND RAZOR BLADE
HOLDER, OR SIMILAR ARTICLE

Morris Greenblatt, New York, N. Y.

Application May 1, 1958, Serial No. 50,688

Term of patent 7 years

(Cl. D58—26)

FIG. 1.

FIG. 2.

FIG. 3.

Fig. 1 is a rear elevational view of a combination coin and razor blade holder, or similar article, showing my new design;

Fig. 2 is a front elevational view thereof; and

Fig. 3 is a top plan view.

I claim:

The ornamental design for a combination coin and razor blade holder, or similar article, substantially as shown.
